Inventor:

Charles Hammer,
By his Attorney Wm. H. Reid.

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

SCALLOP JAR-CLOSURE.

1,293,088.

Specification of Letters Patent.

Patented Feb. 4, 1919.

Application filed June 6, 1918. Serial No. 238,480.

To all whom it may concern:

Be it known that I, CHARLES HAMMER, a citizen of the United States, residing at Queens, in the county of Queens and State 5 of New York, have invented certain new and useful Improvements in Scallop Jar-Closures, of which the following is a specification.

This invention has reference to closures 10 for storage vessels especially those of glass such as bottles and jars, that have screw-threads or lugs on the neck, which closures are provided with inwardly extending projections arranged to engage these lugs or 15 threads, whereby on rotating the closure on top of the bottle it will screw down and be secured thereon by the engagement of these projections with the threads on the bottle or jar.

20 The object of the present invention is to provide a special form of lug or projection on the inside wall of the closure in which a kind of shelf or flange is formed at the top of an upwardly extending projection, that 25 will present a face of a helical nature for engagement with the helical lower face or surface of the thread or lug on the jar or bottle, but which shelf at one end portion is reduced until it merges into the raw free 30 top of the projection, that lies in the same helical surface for engagement with the jar thread. A further object is to provide a closure with a shelf formation of this character, in which the shelf is supported and 35 carried by the projection of the closure flange that extends upwardly inside of the cap, and is inclined inwardly from the cylindrical flange wall, whereby the shelf can have a certain yielding movement radially 40 outward on engagement with the thread on the jar, yet the shelf portion that engages the bottle thread will be strongly supported and can yield only a short distance, and constitute a secure form of closure.

45 In the accompanying drawing showing one embodiment of my invention, Figure 1 is a vertical central section through the closure before the flange projections are bent up to final form. Fig. 2 is a similar view 50 of the closure in the finished condition. Fig. 3 is a bottom plan view of the closure. Fig. 4 is a partial vertical section enlarged taken on the line 4—4 of Fig. 3; and Figs. 5, 6, 7 and 8 are similar views in adjacent

positions through the projections, as indicated by these numbers in Fig. 3.

55 As set forth in the drawing the cap or closure comprises essentially a top 9 and a flange portion 10, shown as cylindrical. On the lower edge of the flange is provided a 60 series of integral projections or lugs 12, four being illustrated. In Fig. 1 these projections are shown extending downwardly and the bottom edge 11 is shown inclined to the plane of the top of the closure, these edges 65 being inclined in the same circular direction in the four lugs set forth.

70 These projections are bent upwardly toward the top 9 of the closure, and the bend is preferably made at the junction of the projection with the flange 10, so that the edge of the bend practically coincides with the lower circular edge of the flange portion, that is, the bottom of the closure or cap extends in a practically unbroken 75 course. The upper portion or margin 11 of each projection is bent over toward the vertical axis of the closure or of the cylindrical portion thereof, whereby to form a kind of shelf 13, and this shelf preferably 80 projects toward the said axis of the closure substantially perpendicular thereto. In other words radial lines perpendicular to the axis, or parallel with the top of the closure would coincide with the upper face 85 of this shelf.

90 This shelf is also arranged whereby its top face is inclined to the plane of the closure top, and as shown extends in a substantially helical direction or path. The upper 95 face of the shelf as shown decreases its distance from the top of the closure gradually from one side edge of the projection toward the other side edge. This shelf 13 is also made of different width considered laterally 100 of the closure in a radial direction, and as shown the shelf has its maximum width at its lowermost portion most remote from the closure top, as indicated by the section of Fig. 4, and also shown in Fig. 3. The consecutive sections show that the width of the shelf decreases as it becomes nearer the top of the shelf. This shelf is shown as terminating a short distance removed from the other end of the lug, and at this portion 105 the up-standing portion 14 of the closure has its free raw edge constituting practically a continuation of the upper surface

of the shelf; but both this surface and the raw edge lie in what is substantially a helical path adapted for engagement throughout its surface and edge, with the under face 5 of the screw-thread or lug on the jar.

This shelf 13 is carried and supported by the inclined connecting portion 14 of the projection 12. It will be seen from Figs. 5-8 that the shelf 13 at its widest portion has a comparatively short wall 14 by which it is supported. In Fig. 5 the supporting wall 14 increases in height with the shelf slightly narrower. In the other views it will be seen that the supporting wall increases in height as the shelf decreases in width radially considered, while at the other end portion the supporting wall 14 is of maximum height, and the shelf has disappeared and is substantially merged 15 into the free or raw edge of the projection 12. It will be further observed from these several sections that the supporting wall 14 is not bent abruptly upward or parallel with the cylindrical flange 10, but extends 20 at an angle thereto. At the same time this supporting wall partakes of the cylindrical curvature of the flange wall, whereby to cause the shelf to lie in a substantially helical path. By this arrangement the shelf 25 13 is at all portions slightly offset from the cylindrical side wall 10, and its distance therefrom increases from its lower portion of greatest width to the upper portion where it merges into the shelf.

30 When a closure of this character is applied to a threaded jar, the lower surface of the jar thread will be engaged by this shelf practically throughout its top face, and also by the free raw lug edge at the 35 end of the shelf. Since the supporting wall 14 of the shelf extends at an angle with the cylindrical side wall of the projection, the shelf can yield outwardly to a certain extent. Also since the supporting wall 14 is inclined inwardly, the shelf may yield slightly in a downward direction, whereby to compensate for irregularity in the thread or lug on the jar, and thereby form a secure and reliable fastening means.

What I claim is:

1. A screw closure for a screw-threaded jar composed of a top and a flange having a plurality of independent projections on the lower edge, each projection being bent back inwardly to extend upward, the upper margin of the projection being bent laterally to form a narrow shelf that extends toward the axis of the closure substantially perpendicular thereto and that decreases in lateral width radially of the closure from one side edge of the projection toward the other edge, at which latter portion the shelf terminates and merges into the free raw edge of the projection, the shelf being inclined to the top plane

of the closure in a helical form whereby its distance from the top decreases from its wide end portion toward the other end.

2. A screw closure for a screw-threaded jar composed of a top and a flange having a plurality of independent projections on the lower edge, each projection being bent back inwardly to extend upward, the upper margin of the projection being bent laterally to form a narrow shelf that extends toward the axis of the closure substantially perpendicular thereto and that decreases in lateral width radially of the closure from one side edge of the projection toward the other edge, at which latter portion the shelf terminates and merges into the free raw edge of the projection, the shelf being inclined to the top plane of the closure in a helical form whereby its distance from the top decreases from its wide end portion toward the other end, the projections below the shelf being each inclined inwardly whereby the shelf is offset from the flange wall a gradually increasing distance from its lower wider end to 80 the upper end thereof.

3. A screw closure for a screw-threaded jar composed of a top and a flange having a plurality of independent projections on the lower edge, each projection being bent back inwardly to extend upward, the upper margin of the projection being bent laterally to form a narrow shelf that extends toward the axis of the closure substantially perpendicular thereto and that decreases in lateral width radially of the closure from one side edge of the projection toward the other edge, at which latter portion the shelf terminates and merges into the free raw edge of the projection, the shelf being inclined to the top plane of the closure in a helical form whereby its distance from the top decreases from its wide end portion toward the other end, the projections below the shelf being each inclined inwardly whereby the shelf is offset from the flange wall a gradually increasing distance from its lower wider end to 90 the upper end thereof.

4. A screw closure for a screw-threaded jar composed of a top and a flange having a plurality of independent projections on the lower edge, each projection being bent back inwardly to extend upward, the upper margin of the projection being bent laterally to form a narrow shelf and that decreases in lateral width radially of the closure from one side edge of the projection toward the other edge, at which latter portion the shelf terminates and merges into the free raw edge of the projection, the shelf being inclined to the top plane of the closure in a helical form whereby 100

its distance from the top decreases from its wide end portion toward the other end.

5. A screw closure for a screw-threaded jar composed of a top and a flange having a plurality of independent projections on the lower edge, each projection being bent back inwardly to extend upward, the upper margin of the projection being bent laterally to form a narrow shelf and that 10 decreases in lateral width radially of the closure from one side edge of the projection toward the other edge, at which latter portion the shelf terminates and merges into

the free raw edge of the projection, the shelf being inclined to the top plane of 15 the closure in a helical form whereby its distance from the top decreases from its wide end portion toward the other end, the projections below the shelf being each inclined inwardly whereby the shelf is off- 20 set from the flange wall a gradually increasing distance from its lower wider end to the upper end thereof.

Signed at New York city, N. Y., on June 4th, 1918.

CHARLES HAMMER.
